UNITED STATES PATENT OFFICE.

ARTHUR M. BEST, OF SHELBY, IOWA.

DRAFT-EQUALIZER.

1,243,243.

Specification of Letters Patent. Patented Oct. 16, 1917.

Application filed December 10, 1915, Serial No. 66,158. Renewed August 21, 1917. Serial No. 187,483.

To all whom it may concern:

Be it known that I, ARTHUR M. BEST, a citizen of the United States, residing at Shelby, in the county of Shelby and State 5 of Iowa, have invented certain new and useful Improvements in Draft-Equalizers, of which the following is a specification.

This invention relates to improvements in draft equalizers, and has for one of its objects to provide a device of this character which may be readily adapted without structural change for three horses, five horses, or six horses.

Another object of the invention is to provide a device of this character including a swinging support to which the draft appliances are coupled so arranged that the swinging support and its attachments may be folded back to occupy less space when 20 not in use.

Another object of the invention is to provide a device of this character of improved construction and increased efficiency.

With these and other objects in view the 25 invention consists in certain novel features of construction as hereinafter shown and described and then specifically pointed out in the claim; and in the drawings illustrative of the preferred embodiment of the 30 invention—

Figure 1 is a plan view of the improved device arranged for six horses;

Fig. 2 is a rear elevation of a portion of the improved device illustrating the construction of the clevis portion of the device;

Fig. 3 is a detached perspective view of the clevis portion of the device;

Fig. 4 is a view similar to Fig. 1 illustrating the arrangement of the device for five 40 horses;

Fig. 5 is a view similar to Figs. 1 and 4 illustrating the device arranged for three horses.

The improved device comprises a main 45 evener beam 10, preferably of wood and of any required size or length, but which will generally be about five and one-half feet in length, but it is not desired to limit the invention in any manner in this respect.

The evener beam 10 is provided with a 50 plurality of apertures designated by the characters 11—12—13 and 14, the apertures 11—12 being located relatively near one end of the beam and the apertures 13—14 relatively near the opposite end of the beam,

the object of the apertures to be hereafter described.

Attached to the beam 10 at one end is a clevis device comprising straps 15—16 bearing upon the upper and lower faces of the beam and projecting beyond one end thereof, as shown. The straps are preferably arranged obliquely to the longitudinal axis of the beam and riveted or otherwise secured at one end, as represented at 17, to the beam. 60 Bearing over the rear end of the beam 10 is a clip device 18 riveted or otherwise secured at 19 to the straps. The straps are perforated at their outer extended ends to receive a pin 20, and mounted to swing upon the pin between the terminals of the strap is a yoke or hanger device 21, the latter being preferably formed of a single strip bent upon itself and mounted to swing at its bend upon the pin. Connected between the sides of the yoke 21 is an endless guard 22, and pivoted at 23 through the guard device 22 and the sides of the yoke 21 is a chain pulley 24. The straps 15—16, the connecting clip 18 and a swinging hanger 70 for the chain pulley constitute a support for the draft appliances which may be turned back upon the pivot 17 to occupy less space when not in use, or when the device is being shipped or stored. A section 75 of chain 25 extends over the pulley 24 and is connected at one end to a double tree 26 and at the other end to a rod 27. The double tree 26 carries the usual swingletrees 28. The rod 27 is of sufficient length to extend between the horses which are hitched to the swingletrees 28 and in advance of the same and coupled at 29 to another double tree 30, the latter having swingletrees 31 of the usual construction. By this 80 arrangement it will be obvious that one team is hitched to the swingletrees 28 and another team hitched to the swingletrees 31, the two teams being thus arranged, one 85 in advance of the other.

Connected to the aperture 13 is a clevis device 32 to which a double tree 33 is connected and carries the usual swingletrees 34. The device thus arranged it will be noted provides for six horses, four at one 90 end of the beam and two at the other end of the beam. When thus employed the plow, harvester or other implement to which the device is to be applied is connected by a clevis 35 to the beam 10 at the aperture 12 110

to equalize the leverage between the teams. When the device is to be employed for five horses the four horses are connected in the same manner as shown in Fig. 1, while the 5 clevis 35 is connected to the aperture 11 and a swingletree 36 connected by a clevis 37 to the aperture 14, the removal of the clevis 35 farther away from the four horse end of the beam equalizing the leverage be- 10 tween the teams.

When the device is to be employed for three horses one of the double trees, for instance the double tree 26 with its swingletrees 28 will be connected directly to the 15 main clevis device, preferably by discarding the rod 27 and utilizing the chain 25 to couple the double tree 26 directly to the pulley 24. The clevis 37 is then transferred to the aperture 13 while the clevis 35 is 20 connected to the aperture 12. By this means the draft is equalized between the teams.

The improved device is simple in con-

struction, can be inexpensively manufactured and adapted without structural change to any required number of draft animals, 25 and may be thus employed for operating gang plows, harvesters, and the like.

Having thus described the invention, what is claimed as new is:—

In a draft equalizer, an evener beam, a 30 clevis device including straps engaging the upper and lower faces of said beam and pivoted at their inner ends thereto, said straps extending beyond one end of the beam and free to swing over the rear face 35 of the same, a clip device bearing around one edge of the beam and connected to said straps and limiting the movement in one direction, and means for connecting draft appliances to said clevis device. 40

In testimony whereof, I affix my signature.

ARTHUR M. BEST. [L.S.]
